(57) **CLAIM**

The ornamental design for tool for expanded cell confinement structure, as shown and described.

DESCRIPTION

FIG. 1 is a perspective view of an embodiment of a device according to my new design;

FIG. 2 is a front view thereof;

FIG. 3 is a rear view thereof, the portions shown in broken lines forming no part of the claimed design;

FIG. 4 is a right side view thereof;

FIG. 5 is a left side view thereof;

FIG. 6 is a top view thereof; and,

FIG. 7 is a bottom view thereof.

The broken lines represent portions of the article and form no part of the claimed design.

1 Claim, 5 Drawing Sheets
